UNITED STATES PATENT OFFICE.

JOHN F. O'CONNOR, OF CHICAGO, ILLINOIS, ASSIGNOR TO WILLIAM H. MINER, OF CHAZY, NEW YORK.

FRICITION SHOCK-ABSORBING MECHANISM.

Application filed April 6, 1921. Serial No. 459,066.

To all whom it may concern:

Be it known that I, JOHN F. O'CONNOR, a citizen of the United States, residing at Chicago, in the county of Cook and State of Illinois, have invented a certain new and useful Improvement in Friction Shock-Absorbing Mechanisms, of which the following is a full, clear, concise, and exact description, reference being had to the accompanying drawings, forming a part of this specification.

This invention relates to improvements in friction shock absorbing mechanisms.

One object of the invention is to provide a friction shock absorbing mechanism especially adapted for railway draft riggings and wherein are obtained high capacity, large frictional wearing areas, certain release, and long life.

Another object of the invention is to provide a mechanism of the character indicated in the preceding and wherein is employed a combined wedging and pressure-transmitting system such that the parts thereof are anti-frictionally mounted with respect to all the friction-generating elements of the mechanism and also wherein the parts of the wedging system are themselves relatively anti-frictionally mounted.

Another object of the invention is to provide a mechanism of the character indicated wherein the pressure per unit of area of friction-generating surfaces is kept relatively low without militating against the desired high capacity, this feature being obtained by employing a greater number of relatively movable friction elements than heretofore.

In the drawings forming a part of this specification, Figure 1 is a horizontal, longitudinal sectional view of a portion of a railway draft rigging showing my improvements in connection therewith. Figure 2 is a vertical transverse sectional view corresponding substantially to the line 2—2 of Figure 1. Figure 3 is a vertical transverse sectional view of the shock absorbing mechanism proper corresponding substantially to the line 3—3 of Figure 1. Figure 4 is a longitudinal sectional view corresponding substantially to the line 4—4 of Figure 3. And Figures 5, 6 and 7 are detail perspectives of one of the wedge elements, one of the so-called movable friction plates, and the spring follower, respectively.

In said drawings, 10—10 denote channel 55 center or draft sills of a railway car to the inner faces of which are secured front stop lugs 11—11 and rear stop lugs 12—12. A portion of a drawbar is indicated at 13, the same being operatively associated with the 60 shock absorbing mechanism proper by means of a hooded cast yoke 14, coupler key 15, and a detachable saddle plate 116.

The improved shock absorbing mechanism proper, as shown, consists, broadly, of a 65 front follower A; a column-load-sustaining member designated generally by the reference B; twin arranged spring resistance C—C; a spring follower D; a series of relatively stationary friction plates E—E; a 70 series of alternated relatively movable friction plates F—F; a plate follower G; a pressure-transmitting block H; two wedge elements K—K; an interposed anti-friction roller L; and outer anti-friction rollers 75 M—M.

The column - load - sustaining member B, as shown, is preferably in the form of a casting suitably formed to contain the springs and other parts of the mechanism. Said 80 member B has an integral rear wall 16 adapted to act as a rear follower in cooperation with the stop lugs 12. Integrally formed with the wall 16 are upper and lower horizontally extended walls 17—17 and 85 vertically extending side walls 18—18 at the outer end thereof as best shown in Figure 3. With this construction, it is evident that the forward end of the member B is of rectangular box-like form and the sides are open 90 rearwardly of the box-like construction to admit of the insertion and removal of the springs C—C and follower D.

As shown, the series of alternated plates E and F are preferably arranged in two 95 groups on opposite sides of the center line of the mechanism. To permit of this, the member B is formed with transversely extending shoulders 19 and 20 on opposite sides of the center as best shown in Figure 4, 100 to thereby provide transversely extending recesses 21 in which are received the ends of the relatively stationary friction plates E. As will be understood, the latter are inserted centrally of the opening at the front end of 105 the column member B and then slipped sideways into proper position on each side of the center line. With this construction, it

- is evident that the plates E are prevented from any appreciable longitudinal movement with respect to the column member B but are free to shift laterally as pressure is imposed thereon. The other series of plates F is alternated with the plates E, as best shown in Figures 1 and 3. Each of the relatively stationary plates E is preferably grooved or channeled on its side facing the center line of the mechanism as indicated at 22 in Figure 3 and the movable plates F are slidably guided within said grooves or channels 22. As seen from Figure 3, the relative depth of the grooves 22 and thickness of the movable plates F is made such that the plates E do not come into contact with each other and hence all may be subject to the lateral pressure hereinbefore mentioned.
- 20 The movable plates F are attached to the plate follower G preferably by notching each of the plates F as indicated at 23 in Figure 4 which notches correspond to transversely extending ribs 24 on the upper and lower inner faces of the follower G. The outermost edges of the plates F engage the inner face of the front wall 25 of the follower G, as best indicated in Figure 1. In this connection, it will be understood that the ribs 24 extend only part way toward the center of the follower G so that the plates may be assembled by first alining the notches thereof with the ribs 24 and then slipping the plates F laterally along the ribs. In the instance shown, the ribs and notches are made semi-circular but, as will be understood by those skilled in the art, this shape may be changed without affecting the function of the mechanism. It will be noted that, in normal position of the parts, the inner ends of the plates F are within the so-called stationary plates E.
- The follower G has a central opening of rectangular form as indicated at 26 through which extends the block H. The latter is in engagement with the main front follower A and, in normal position of the parts, the outer face of the follower G is spaced from the follower A a small distance, preferably about a half inch. The block H bears against the outer end of one of the triangular wedge elements K. The elements are of like construction but oppositely arranged, each having a flat bearing face as indicated at 27 in Figure 5. On its outer side each element K is recessed as indicated at 28 within which is disposed a preferably steel wear plate 29 forming a bearing for the corresponding pair of anti-friction rollers M—M. The opposite walls defining the sides of the recess 28 are transversely grooved as indicated at 30 to accommodate the ends of the rollers M and permit the latter a free rolling movement within limits as best seen in Figure 1. On its sloping or wedge face proper, each element K is recessed as indicated at 31 at the bottom of which is placed a steel plate insert 32 forming a bearing for the common anti-friction roller L. Suitable shoulders 33 are formed on the elements K to limit the movements of the roller L in one direction with respect to each element K. The innermost element K bears against the spring follower D as shown in Figure 1. In this connection, it will be observed that the outside rollers M bear against a movable friction plate F.
- The spring follower D, shown detached in Figure 7, preferably comprises a rectangular plate section 34 against which bear the forward ends of the two springs C—C and forwardly extended side arms 35—35 which straddle the wedge elements K and, in normal position of the parts, engage the inner edges of the plate follower G as best shown in Figure 4. The plate section 34 of the follower D is cut away at its ends as indicated at 36 so as to seat within corresponding notches 37 formed in the column member B.
- The operation of the device is as follows. Assuming an inward or buffing movement of the drawbar, the front follower A is forced inwardly or rearwardly, the column member remaining stationary since it is held by the rear stops 12. In taking up the space, a half inch or thereabouts, between the follower A and the plate follower G, the load from the drawbar is transmitted directly through the block H to the wedging elements K—K and the latter, considered as an entirety, moved longitudinally relatively to the innermost plates F which action is permitted as a result of the rolling of the rollers M thereon. During this initial movement of the wedging system with respect to the friction plates, the lateral pressure exerted outwardly against the two groups of alternated plates is increased and the spring follower D is forced inwardly a slight distance away from the inner edges of the stationary plates E and thereafter the inner end of the wedging system is afforded a yielding spring resistance proportional to the degree of compression on the springs. After the follower A engages the outer face of the plate follower G, the latter is forced rearwardly as are also the plates F. Simultaneously therewith, the wedging system will also move rearwardly as will be understood. The lateral spreading pressure having previously been set up in all of the friction plates, the frictional resistance during the remainder of the stroke will be graduated and of uniform character and, because of the ten sets of cooperating friction faces, a very high capacity will be developed. From the preceding, it will be observed that the action of the mechanism during the compression stroke will be smooth and that there is

no danger of excessive pressure being exerted on any particular element for the reason that the ultimate expanding or wedging force is determined by the spring.

- 5 In release upon removal of the actuating force, the spring first reacts through the spring follower D and forces the wedging system outwardly relatively to the so-called movable friction plates F and plate follower G and until the follower A is separated from the follower G an amount corresponding to the normal spacing therebetween illustrated in Figure 1. This action is greatly facilitated and the certainty of release insured because of the anti-friction rolling bearings between the system as an entirety and the innermost plates F and also by the anti-friction rolling bearing between the two elements K of the wedge system.
- 10 When the wedge system has thus been collapsed and forced outwardly relatively to the movable plates F and follower G, the outer ends of the side arms 35 of the spring follower D engage the follower G and hence 15 the latter while carrying the plates F is forced outwardly or back to its normal position under the expansion of the springs C. From the preceding it will be observed that the lateral pressure on all of the friction elements will have been reduced substantially 20 to zero before there is any outward pull imposed upon the plates F.
- 25

As will be understood by those skilled in the art, the members B and G may be readily and cheaply manufactured as ordinary castings inasmuch as no frictional wearing surfaces on either are required; the plates E may be readily manufactured at comparatively small expense preferably by rolling 30 strips of the desired channel formation and cutting them off to length; and the plates F may also be readily manufactured in the form of rolled plates, both sets of plates being case hardened if desired.

- 35 45 As is well known to those skilled in the art, it is desirable that the over-all length of the mechanism be maintained and also all of the parts held in assembled relation to facilitate shipment. To this end, I may employ a pair of retainer bolts 38 having the nuts and heads thereof seated in suitable 50 sockets carried by the block H and rear wall of the member B, said bolts extending through suitable aligned perforations or recesses in the various parts in order to avoid 55 interference during the action of the mechanism.

I have herein employed the term column-load-sustaining member for the member 60 referenced B and although the same is shown of casing or container form, it will be evident to those skilled in the art, that the same may take other different forms without departing from the spirit of the invention. All changes and modifications are

contemplated that come within the scope of the claims appended hereto.

I claim:

1. In a friction shock absorbing mechanism, the combination with a column-load-sustaining member; of a plurality of friction elements mounted thereon and relatively immovable longitudinally thereof; of a spring resistance; a plurality of relatively movable friction elements alternated with 70 said first named friction elements and longitudinally movable with respect thereto; a follower to which said movable friction elements are attached; and wedge-pressure-transmitting means reacting at the inner 80 end against said spring resistance and laterally against said alternated friction elements to augment the friction therebetween, said means, at the outer end, extending beyond said follower a limited distance and adapted 85 to be pressure-actuated a limited distance prior to and thereafter simultaneously with said follower.

2. In a friction shock absorbing mechanism, the combination with a column-load-sustaining member; of a plurality of friction elements mounted on said member and relatively immovable longitudinally thereof; of a plurality of relatively movable friction elements alternated with said first named 90 friction elements and longitudinally movable with respect thereto, said immovable and movable friction elements being divided into two laterally opposed groups; a spring resistance; wedge-pressure-transmitting means 100 interposed between said two groups and reacting laterally against both groups, said means reacting at the inner end against said spring resistance and adapted to receive the actuating force at the outer end; and means 105 independent of said wedge-pressure-transmitting means acted upon by said spring resistance during the release action of the mechanism arranged to pull said movable friction elements outwardly from their 110 outer ends.

3. In a friction shock absorbing mechanism, the combination with a column-load-sustaining member; of a plurality of friction elements mounted on said member and relatively immovable longitudinally thereof; of a plurality of relatively movable friction elements alternated with said first named 115 friction elements and longitudinally movable with respect thereto, said immovable and movable friction elements being divided into two laterally opposed groups; a spring resistance; wedge-pressure-transmitting means interposed between said two groups and reacting laterally against both groups, 120 said means reacting at the inner end against said spring resistance and adapted to receive the actuating force at the outer end; and means acted upon by said spring resistance during the release action of the mechanism 125

arranged to pull said movable friction elements outwardly from their outer ends, said last named means including a follower at the outer ends of and attached to said movable friction elements, and pressure-transmitting means interposed between said spring resistance and said follower.

4. In a friction shock absorbing mechanism, the combination with a column-load sustaining member; of a plurality of friction elements mounted on said member and relatively immovable longitudinally thereof; of a spring resistance; a plurality of relatively movable friction elements alternated with said first named friction elements and longitudinally movable with respect thereto; a follower to which said movable friction elements are rigidly attached; a spring follower located between said immovable friction elements and the adjacent portions of the spring resistance; wedge-pressure-transmitting means reacting at the inner end against said spring follower and laterally against said alternated friction elements to augment the friction therebetween, said means, at the outer end, extending beyond said follower to which the movable friction elements are attached for a limited distance and adapted to be pressure-actuated a limited distance prior to and thereafter simultaneously with said follower.

5. In a friction shock absorbing mechanism, the combination with a column-load sustaining member; of a plurality of friction elements mounted on said member and relatively immovable longitudinally thereof; of a spring resistance; a plurality of relatively movable friction elements alternated with said first named friction elements and longitudinally movable with respect thereto; a follower to which said movable friction elements are rigidly attached; a spring follower located between said immovable friction elements and the adjacent portions of the spring resistance; wedge-pressure-transmitting means reacting at the inner end against said spring follower and laterally against said alternated friction elements to augment the friction therebetween, said means, having a non-compressible outer end, extending beyond said follower to which the movable friction elements are attached for a limited distance and adapted to be pressure-actuated a limited distance prior to and thereafter simultaneously with said follower, said wedge-pressure-transmitting means including a plurality of wedge elements one of which bears upon said spring follower, and anti-friction means between said elements; and anti-friction means interposed between said wedge-pressure-transmitting means and the friction elements.

6. In a friction shock absorbing mechanism, the combination with a column-load

sustaining member; of a plurality of friction elements mounted on said member and relatively immovable longitudinally thereof; of a spring resistance; a plurality of relatively movable friction elements alternated with said first named friction elements and longitudinally movable with respect thereto; a follower to which said movable friction elements are rigidly attached; a spring follower located between said immovable friction elements and the adjacent portions of the spring resistance; wedge-pressure-transmitting means reacting at the inner end against said spring follower and laterally against said alternated friction elements to augment the friction therebetween, said means, at the outer end, extending beyond said follower to which the movable friction elements are attached for a limited distance and adapted to be pressure-actuated a limited distance prior to and thereafter simultaneously with said follower; and pressure-transmitting means interposed between said spring follower and the other follower adapted to transmit the reactive spring pressure to said other follower and thereby pull the movable friction elements outwardly during release.

7. In a friction shock absorbing mechanism, the combination with a casing having a plurality of relatively stationary friction plates mounted therein; of a spring resistance; a follower interposed between said spring resistance and the inner ends of said plates; a plurality of relatively movable friction plates alternated with said stationary friction plates, said alternated plates being divided into two laterally opposed groups; a plate follower to which said movable friction plates are attached; pressure-transmitting means interposed between said two followers and movable relatively to said plate follower; and combined wedge-pressure-transmitting means reacting at the inner end against said spring follower and laterally against said friction elements, said means being adapted to receive the actuating force initially prior to said plate follower.

8. In a friction shock absorbing mechanism, the combination with a casing having a plurality of relatively stationary friction plates mounted therein; of a spring resistance; a follower interposed between said spring resistance and the inner ends of said plates; a plurality of relatively movable friction plates alternated with said stationary friction plates, said alternated plates being divided into two laterally opposed groups; a plate follower to which said movable friction plates are attached; pressure-transmitting means interposed between said two followers; combined wedge-pressure-transmitting means reacting at the inner end

against said spring follower and laterally against said friction elements, said means being adapted to receive the actuating force initially prior to said plate follower; and 5 antifriction means interposed between said wedge pressure-transmitting means and each group of friction elements.

In witness that I claim the foregoing I have hereunto subscribed my name this 12th day of Mar. 1921.

JOHN F. O'CONNOR.
